Tracy P. Jong; Cheng Ning Jong(57) **CLAIM**

The ornamental design for a rabbit figure head, as shown and described.

DESCRIPTION

FIG. 1 is a front view of the first embodiment of a rabbit figure head, showing my new design.

FIG. 2 is a rear view thereof.

FIG. 3 is a right side view thereof.

FIG. 4 is a left side view thereof.

FIG. 5 is a bottom view thereof.

FIG. 6 is a top view thereof.

FIG. 7 is a top right front perspective view thereof.

FIG. 8 is a bottom left front perspective view thereof.

FIG. 9 is a front view of a second embodiment of a rabbit figure head.

FIG. 10 is a rear view thereof.

FIG. 11 is a front view of a third embodiment of a rabbit figure head.

FIG. 12 is a rear view thereof.

FIG. 13 is a front view of a fourth embodiment of a rabbit figure head; and,

FIG. 14 is a rear view thereof.

The broken lines shown throughout the views represent environmental structures connected to a rabbit figure head or the portions of the design that form no part of the claim.
